Inventor

UNITED STATES PATENT OFFICE.

FRANK SELIG, OF CLEVELAND, OHIO.

PROTECTIVE TIP.

Application filed January 19, 1925. Serial No. 3,409.

To all whom it may concern:

Be it known that I, FRANK SELIG, a citizen of the United States, residing at Cleveland, in the county of Cuyahoga and State of Ohio, have invented certain new and useful Improvements in Protective Tips, of which the following is a specification.

My invention relates to improvements in protective tips or sheaths, the present embodiment of the invention being particularly designed and adapted for use as a resilient protective covering or sheath for the ends of article handles, shafts, rods, and the like, of widely varying forms and types.

The primary object of the invention is to provide a generally improved protective tip or sheath of the character indicated, which will be exceedingly simple in construction, cheap of manufacture and efficient in use.

A further and very important object is the provision of a resilient protective cap or sheath which may be readily attached to the end of the handle or shaft to be protected without the use of tools and when applied will be very securely retained in position and when applied acting as a cushioning and protecting medium.

A further and important object is the provision of a protecting tip or cap which may be readily conformed to and applied upon the tip or end portions of articles of widely varying forms and dimensions, and with this end in view the protective cap or sheath is provided with a normally constricted mouth or neck provided with internally arranged axially inclined annular fins or projections movable in an enlarging direction when the cap or tip is placed over the end of the article to be protected and closing over the latter in a constricting or clamping direction with a toggle-like action when moved relatively in an opposite or article and cap withdrawing direction.

With the above mentioned and other ends in view, the invention consists in the novel construction, arrangement and combination of parts, hereinafter described, illustrated in some of its embodiments in the accompanying drawings, and particularly pointed out in the appended claims.

Referring to the drawings, forming a part of this specification, Figure 1 is a side elevation of a protecting tip, constructed in accordance with this invention, and applied to the tip of an article handle.

Fig. 2, a central longitudinal sectional

view of the same, detached, the article handle being indicated in dotted lines for indicating the relative arrangement and co-action of the handle centralizing and gripping elements when the protective tip or cap is applied.

Fig. 3, a side elevation of another form applied to an article handle or stick of the golf club type, and particularly designed and adapted for use in such connection.

Fig. 4, a central longitudinal sectional view of the same, detached.

Fig. 5, a side elevation of another form applied to and particularly designed for use in connection with a household article handle, such as a broom, mop, or the like.

Fig. 6, a central longitudinal sectional view of the same, detached.

Similar numerals of reference designate like parts throughout all the figures of the drawings.

The improved protective tip or cap is preferably formed of resilient material, such as a high grade of vulcanized rubber, and the protective sheath or body portion 1, may be of any suitable and convenient form or type, and as a convenient means of readily attaching or mounting the same upon the end of an article handle or shaft 2, the body or sheath is provided with a suitable socket or receptacle and is also provided with a constricted handle receiving opening 1^a, formed by means of the constricted neck portion 1^b. The walls of the sheath or cap are preferably tapered both exteriorly and in thickness from the base to the mouth of the handle receiving opening 1^a, as shown.

As a means of enabling the cap or tip to be readily passed over the tip of the handle or shaft 2, and particularly as a means of securing or locking the protecting tip or cap in position, and also as a further means of providing a wide adjustment and adaptability of the same to handles of varying forms and contours and relatively wide variations in diameters, the interior of the handle receiving neck or opening is provided with a plurality of axially inclined and tapered overhanging annular fins or projections 1^c, said tapered fins or projections being undercut and spaced apart so as to be movable in an enlarging direction overlapping relation as the cap or sheath is moved over the end of the article handle or shaft 2 and frictionally engaging and closing over the latter in separating relation

and in a constricting direction with a toggle-like action when moved relatively in an opposite direction, as in withdrawing the cap or tip therefrom.

- 5 As a means of providing an annular cushioning chamber about the tip of the handle and providing an impact receiving rim portion 1^a, the interior of the cap or tip may be provided with a handle receiving and centralizing beading or fin 1^c, beneath the top or crown portion of the cap, said annular beading or fin 1^c acting to centralize the crown portion of the tip or cap relative to the tip of the handle irrespective of varying contours in the latter and also spacing the walls of the cap or sheath away from the handle forming an annular air chamber 1^f, which becomes sealed up or closed through the toggle acting fins 1^e.
- 10 20 In the form shown in Figs. 5 and 6 of the drawings the cap or protecting tip is in the specific form of a bulb surrounded by a projecting rim or beading 1^c, and it will also be apparent upon reference to Figs. 2 and 6 of the drawings that the crown portion of the tip or cap is of concavo-convex formation, forming a subjacent or intervening air chamber 1^b, immediately above the tip end of the handle or shaft 2.
- 15 30 Having thus described some of the embodiments of my invention, without having attempted to set forth all the forms in which it may be made, or all the modes of its use, what I claim and desire to secure by

35 Letters Patent is,—

1. In a device of the character described, a handle, and a protective tip having axially spaced resilient handle receiving and centralizing elements conjointly with said handle and tip forming an annular air cushioning chamber.
- 20 2. A protective tip, comprising a protective tip body having a constricted handle receiving opening armed on its inner pe-

riphery with annular axially inclined overhanging tapered fins opening and enlarging in overlapping relation when moved relatively of the handle as the tip body is placed on the latter and closing in a constricting direction with a toggle-like action upon the handle when moved relatively in an opposite or handle withdrawing direction.

3. In a device of the character described, a resilient protective sheath having a neck armed within with axially inclined and tapered projections, said fin-like projections being undercut and overhanging and opening and enlarging in overlapping relation as moved over and placed in position on the end of the article and closing in separating relation with a toggle-like action as moved relatively in an opposite or article withdrawing direction.

4. In a device of the character described, a receptacle shaped protective tip having a handle receiving and centralizing annular projection within the top portion thereof and provided with a constricted handle receiving neck having axially inclined fin-shaped projections adapted to be opened and enlarged when the tip is moved relatively over the handle and to close and clamp the same with a toggle-like action when moved in an opposite direction.

5. A protective tip for handles comprising a protective tip body having a constricted handle-receiving opening and provided with an annular axially inclined undercut fin for engagement with the handle when the tip is placed thereon, said fin opening and enlarging when moved relatively to the handle as the tip body is placed on the latter, and closing in a constricting direction when moved relatively in the opposite or withdrawing direction.

In testimony whereof I have affixed my signature.

FRANK SELIG.
